H. SCHMARROW.
SAFETY JEWEL CHEST.
APPLICATION FILED NOV. 25, 1911.

1,028,910.

Patented June 11, 1912.

UNITED STATES PATENT OFFICE.

HERMAN SCHMARROW, OF NEW YORK, N. Y.

SAFETY JEWEL-CHEST.

1,028,910.

Specification of Letters Patent. Patented June 11, 1912.

Application filed November 25, 1911. Serial No. 662,261.

To all whom it may concern:

Be it known that I, HERMAN SCHMARROW, a citizen of Germany, residing at New York city, county and State of New York, 5 have invented a new and Improved Safety Jewel-Chest, of which the following is a specification.

This invention relates to a chest of novel construction for containing money, jewelry 10 and other valuables, in which an alarm is automatically set off as soon as the device is shifted along or raised off its support.

Means are also provided for starting the alarm each time the chest is opened by 15 false keys or by special keys in the possession of employees, etc., while a master key intended for the exclusive use of the owner will open the box without setting off the alarm.

20 The chest is further provided with means for sounding the alarm in case the lid is pried open, said means being so constructed, however, as to be rendered ineffective when the cover is raised after properly opening 25 the chest-lock.

In the accompanying drawing: Figure 1 is a plan of a chest embodying my invention, showing the chest opened and the false bottom removed; Fig. 2 an enlarged 30 vertical section on line 2—2, Fig. 1; Fig. 3 an inner view partly in section of the chest-front; Fig. 4 a detail of the contact lever for the alarm mechanism; Fig. 5 an enlarged vertical section on line 5—5, Fig. 35 3; and Fig. 6 a wiring diagram.

Upon the bottom 10 of the metal chest A is mounted an insulating plate 11 that supports the alarm mechanism proper, the latter being normally covered by a false bottom 12 which rests on ledges 13 of plate 11. 40 Into a central perforation of plate 11 is fitted an inverted cup-shaped member 14, the open mouth thereof registering with a corresponding central opening 15 of bottom 10. Cup 14 is provided with an upwardly 45 extending tubular stem or sleeve 16 in which is slidably mounted a plunger 17, the latter being normally depressed by a suitable spring 18. Into a lower eye 19 of plunger 17, is inserted an S-shaped link 20 from which depends a disk or shoe 21, the lower face of said shoe being covered with a layer 22 of felt, rubber or similar friction increasing material. Plunger 17 is trav-

ersed by a horizontal pin 23 that is accommodated within corresponding slots 24 of stem 16 and has a bent end 25 adapted to engage a contact spring 26 which is mounted on plate 11. The other straight end of pin 23 is adapted to be engaged by the arm 27 formed on an oscillating rod 28 that is mounted in suitable brackets 29 of plate 11. Rod 28 is provided with a hand lever 28^a located in proximity to the front 30 of chest A and projecting upward through a corresponding slot of false bottom 12.

The alarm proper consists of a pair of electromagnets 31, the vibratory armature 32 of which carries a hammer 33 adapted to be thrown against the rear plate 34 of chest 70 A, thereby giving the desired alarm. The spring 35 of armature 32 is adapted to engage a contact screw 36 tapped into a post 37 of plate 11. Below screw 36, there is rotatably mounted on post 37, a contact lever 75 38, a coiled spring 39 tending to turn said lever in the direction of the arrow a (Fig. 1). The forward arm of lever 38 carries a button 40 which is adapted to be engaged by arm 27 of rod 28, while the beveled rear arm of lever 38 is adapted to engage a nose 41 of armature 32. In proximity to the rear arm of lever 38, there is further mounted upon plate 11 a post 42, traversed by a contact pin 43 which is adapted to be 85 engaged by said rear arm. Contact spring 26 is by wire 44, connected to post 37, while a wire 45 leads from armature 32 to a battery 46. The latter is, by wire 47 connected to electromagnets 31 which are in turn by 90 wire 48 connected to post 42, said post being by wires 49, 50 connected to post 37.

As thus far described, the operation is as follows: After the chest has been transferred to its proper keeping place, the lid 51 thereof is opened and handle 28^a is swung 95 toward the right (Figs. 1 and 2), so that arm 27 will engage pin 23 thereby raising the latter together within plunger 17 against the action of spring 18. The correlation of the parts is such that when plunger 17 is fully raised, disk 21 will be lifted slightly off its support, so as to insure a true vertical alinement of the parts 17, 20 and 21 by gravity. Handle 28^a is now returned 100 into its original position, thereby withdrawing arm 27 from pin 23, while the parts 17, 20 and 21 will retain their vertically alined

position, thereby preventing a descent of plunger 17 and pin 23 (Fig. 2). Lid 51 is finally closed and locked by properly turning the master key within lock 52. If chest 5 A is now shifted along its support, disk 21 will not participate in this movement owing to its friction upon said support, so that the parts 21, 20 and 17 will be brought out of vertical alinement, whereby plunger 17 10 loses its support. In this way, spring 18 is free to lower the plunger, so as to bring pin 23 into engagement with contact 26, thereby closing an electric circuit, the current flowing from source of electricity 46 15 through wire 47, electromagnets 31, wires 48, 42, 49 50, stem 16, plunger 17, pin 23, contact 26, wire 44, post 37, screw 36, armature spring 35 and wire 45 back to source 46. In this way, armature 32 and hammer 20 25 33 will be oscillated owing to the alternating breaking and closing of the electromagnet circuit, as will be readily understood. The alarm will continue to ring until lid 51 is opened and lever 28^a is again manipulated to raise plunger 17 and thereby break contact between the parts 23, 26. It is obvious that the alarm will not only be set off upon a shifting of the chest along its support, but also upon a lifting of the chest off 30 35 said support, in which case the plunger 17 will be free to descend to close the electric circuit hereinabove referred to.

Additional means are provided for setting off the alarm if a spurious key or a key 35 specially prepared for employees is used for opening the chest. These means are shown to consist of a contact stud 53 insulated from the metallic lock case 54 and conductively connected by a bridge 55 to an insulated 40 binding post 56, the latter being by wire 57 connected to contact spring 26. Stud 53 is so located with respect to the key-pivot 58, that the master key, part of the contour of which is indicated by the dotted line 59 45 in Fig. 5, will clear said stud. The employee's key 60, however, is so profiled (full lines in Fig. 5) that during its rotation it will touch stud 53 and thereby close an electric circuit, the current flowing as follows: 50 from battery 46 through wire 47, electromagnets 31, wires 48, 49, 61, metallic case 54, key 60, stud 53, bridge 55, post 56, wire 57, spring 26, wire 44, post 37, screw 36, armature spring 35 and wire 45 back to 55 battery 46. As after the first attraction of the armature 32, nose 41 will clear lever 38, spring 39 is thus free to tilt said lever into engagement with pin 43. An auxiliary circuit is thus formed which causes a continuance of the alarm, even after key 60 has 60 cleared stud 53, the current flowing from battery 46 through wire 47, electromagnets 31, wire 48, post 42, pin 43, lever 38, post 37, screw 36, armature spring 35 and wire 45 back to battery 46. For discontinuing 65

the alarm, lid 51 is opened and handle 28^a is once oscillated, whereby arm 29 by engaging button 40 will swing lever 38 in a direction opposite to arrow α (Fig. 1) until said lever falls in behind nose 41 and is thus 70 locked in position. In this way the flow of the electric current from pin 43 to lever 38 is interrupted and the alarm silenced.

Further additional means are provided which sound the alarm, if the lid 51 of chest 75 A is fraudulently pried open, such means consisting of a stud 62 depending from said lid and adapted to engage a contact spring 63 secured to one of the lock bolts 64. The bent free end of spring 63 is adapted to engage a pin 65 insulated from case 54 and connected by wire 66, to post 56 and consequently to wire 57. The relative arrangement of parts 63 and 65 is such that upon a partial raising of lid 51, spring 63 will come 80 into contact with pin 65 to close a circuit. The current of this circuit flows from wire 66 in a manner similar to that described with respect to the contact between parts 53, 60, the latter being replaced by the 85 parts 63, 65. The alarm will thus also continue to be sounded, even after the prying tool has been withdrawn from underneath lid 51. The last described alarm sounding means are rendered ineffective when the 90 bolt 64 is retracted by the manipulation of a proper key, in which case the bent end of spring 63 is shifted beyond pin 65, so that said spring will not come into contact with pin 65 even after stud 62 has cleared spring 95 63 during the opening of the lid.

Although the means for automatically continuing the alarm after being set off have been described in connection with the insertion of a spurious key into the chest 105 lock, it is obvious that these means are likewise set in action as soon as the circuit has been closed by lifting, shifting or otherwise tampering with the chest. In this way, the latter is fully protected against any attempts to remove or fraudulently open the same.

I claim:

1. A chest having an apertured bottom, a tubular sleeve extending upwardly therefrom, a spring-influenced plunger slidable in said sleeve, a link depending from the plunger, a friction shoe depending from said link, the shoe and link being accommodated within the bottom aperture, an electric 115 alarm within the chest, and an alarm circuit controlled by the plunger.

2. A chest provided with an inverted cup-shaped member inserted into the chest-bottom, a tubular sleeve extending upwardly 120 from said member, a spring-influenced plunger slidable in said sleeve, a link depending from the plunger, a friction shoe depending from said link, the shoe and link being accommodated within the cup-shaped mem- 130

ber, an electric alarm within the chest, and an alarm circuit controlled by the plunger.

3. A chest provided with a lid, a lock-bolt for said lid, a contact spring carried by
5 said bolt, a stud depending from the lid and adapted to engage the contact spring, a fixed contact pin adapted to be engaged by the

spring, an electric alarm within the chest, and an electric alarm circuit controlled by said contact spring and pin.

HERMAN SCHMARSOW.
